(57) **CLAIM**

I claim the ornamental design for a pocket square, as shown and described.

DESCRIPTION

FIG. 1 is a front view of the pocket square.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a perspective view of the claimed design as it appears inside a pocket.

The cross-hatching lines in the drawings show shading that defines the contours of the pocket square and do not reflect a particular surface ornamentation or material.

The broken lines of the garment in FIG. 7 depict environmental structure to assist how the pocket square may appear when worn, but form no part of the claimed design. The broken lines along the surface of the pocket square depict claimed stitching.
